UNITED STATES PATENT OFFICE.

OLIVER P. COLLINS, OF MCKEESPORT, PENNSYLVANIA, ASSIGNOR OF ONE-THIRD TO THOMAS Y. CROSS AND ONE-THIRD TO BYRD REESE FEE, BOTH OF PITTSBURGH, PENNSYLVANIA.

MACHINE FOR FOLDING AND SHEARING SHEET METAL.

1,221,686.

Specification of Letters Patent.

Patented Apr. 3, 1917.

Application filed July 13, 1915. Serial No. 39,611.

To all whom it may concern:

Be it known that I, OLIVER P. COLLINS, a citizen of the United States, residing at McKeesport, in the county of Allegheny and

5 State of Pennsylvania, have invented certain new and useful Improvements in Machines for Folding and Shearing Sheet Metal, of which the following is a specification.

My invention relates to that class of machines which is designed to fold sheet metal, such as tin plate, etc., and my particular object is to provide a machine which will receive a plurality of metal sheets which are cut to approximately the desired size, to fold 10 them together upon their middle line, and to shear the ends to exact uniformity on a true line.

In order to accomplish this object, I provide means for receiving the plates, means 20 for adjusting them in a true position relative to my machine and to hold them in such position, and means to fold them together and simultaneously shear off the ends of the plates, leaving them a predetermined size.

25 In rolling very thin metal plates, such as tin plate, it is necessary to roll a plurality of sheets together, since the rolls will not accurately operate to the minimum thickness required for a single plate. Therefore 30 it is customary to roll the single plates as thin as can be done conveniently, then to fold two of the sheets together, making a four ply infolded set of sheets, and again to roll this set to the minimum thickness, etc.

35 My machine is designed to do this folding. The plates come from the rolls with one end ragged, and with the side portions extending longitudinally beyond a middle receding portion in the form of a fish tail. I provide 40 means for shearing the ragged end to a true line, while they are being folded.

Further objects and functions of the machine will appear in the specification below.

Referring to the drawings,—

45 Figure 1 is a view in sectional elevation showing the general arrangement of my machine and its driving mechanism.

Fig. 2 is a cross section through the folding table on the line II. II. of Fig. 1, showing 50 the arrangement of an air cylinder and

the adjusting and gripping forks operated thereby.

Fig. 3 is a plan view of the folding table in open position.

Figs. 4 and 5 show the details of a clutch, 55 and a foot pedal designed to operate it.

The construction and operation of my machine is as follows:

A motor M drives gear wheel 12 by means of intermediate gear wheel 11. Connected 60 to the shaft 13, upon which is fixed the wheel 12, is the crank 14, which in turn is connected by link 15 to the gear sector 16. The link 15 is pinned loosely at each of its ends. The gears of sector 16 mesh with the 65 gears of sector 17, which is fixed on a shaft 18. The folding member or platen 19 is also fixed on the shaft 18. This member has at its outer edge a flange 19^a which is adapted to retain on its inner side a detachable cutting knife 20 by any suitable form of attachment, such as bolts 21. This folding member is of such dimensions that when turned over upon the table 22 the knife 20 will just pass over the knife 23 which is set 70 on the outer edge of the table, and shear off the surplus from the folded plates.

The operator stands on the side having the folding member and feeds the metal sheets onto the table members, shoving them forward until their inner ends bear against the face of knife 20 and their outer ends rest against the spring supported guard 38, by their middle receded portions. In order to square the sheets upon the table and insure 85 that they exactly conform to each other edgewise without overlap, laterally moving arms 24 are provided. Slots 25 in the table 22 are left, through which the arms 24 operate. Corresponding slots 25^a are provided 90 in the folding member 19. By making these slots of considerable length I adapt my machine to handle plates of varying width.

Arms 24 at one side and arms 24^a at the other side of the middle portion of table 22 95 are normally apart a sufficient distance to admit of the placing of a number of assembled sheets, and said arms define the corners of a rectangle. A cylinder 26 having therein a piston adapted to be operated by com- 100

pressed air or other fluid, and a shaft 27, connected to a lever 28, which in turn is pinned on the bar 29, and which has connecting links 30 and 31 above and below its 5 pivoted point respectively, is provided.

These links at their other ends are connected to the sleeves 32 and 33 respectively, which in turn carry the two arms or prongs 24 and 24^a respectively.

10 It will be understood that a source of compressed air 51 is connected through four-way valve 52 and suitable pipes to the cylinder 26, so that the prongs 24 and 24^a are positively operated in each direction. Therefore they will grip the edges of the sheets and bring them into alinement and hold them tightly until the operator throws valve 52 to release them.

15 It will be understood that the sleeves are carefully fitted on the bar 29 so that they and the prongs move accurately laterally with respect to the table 22. By this means, when a plurality of metal sheets are put on the table 22, and air is introduced into the cylinder 26, so as to draw the piston in, the arms or prongs 24 and 24^a will be moved inward to grip the sides of the stack of plates. Since the prongs are made square with respect to the table, and considerable pressure 20 is applied, the plates will be trued up with respect to each other, and with respect to the table, and will be held tightly.

25 The gear wheel 12 rides loosely on the shaft 13, upon which is fixed the crank 14. A clutch is provided by which the wheel 12 is made to drive the shaft 13 intermittently. This clutch is not, *per se*, a part of my invention, and may be of any desired construction. There are several standard makes now on 30 the market, and one form is shown in the drawings in Figs. 4 and 5.

35 The clutch is designed to be operated by a foot pedal 34 and a plunger 34^a which engages a cam 35 on the sleeve 36 which is splined on the shaft 13. A spring 37 about the shaft exerts pressure to force the teeth on the sleeve 13 into mesh with teeth on the gear wheel 12. However, the cam on the inner face of the sleeve 36 bearing against 40 the plunger 34^a of pedal 34 is so designed that at each revolution this cam rides up against the fixed plunger 34^a, moves the sleeve laterally, and throws the teeth out of mesh.

45 To release the sleeve and allow it to be thrown back into mesh by pressure of coil spring 37, it is necessary to force downward the plunger 34^a out of engagement with cam 35. The operation of this clutch will be obvious to all who are familiar with such devices. By this means the shaft 13 and the crank 14 make one complete revolution and then stop, and are only started by release of the foot pedal 34. It will be apparent that the operation is continuous if the pedal is 50 kept down.

In operation, a plurality of metal plates are placed on the table member with the receding middle portions of their ragged ends resting against guard 38; the air piston is operated to bring the prongs 24, 24^a, inward 75 so as to straighten the plates out in reference to the table member and to bring them into proper position relative to each other and to the stationary member; the foot pedal is used to set the press driving mechanism in 80 operation; the member 19 folds over upon the stationary table member 22, thereby creasing the plates at their middle point and overlapping them in folded position between the table members. The knife members 20 and 23 shear off all of that end of the plate which protrudes beyond the edge of the stationary table member. In the shearing operation, the advancing end of shear blade 20 abuts against the end of guard 38, depressing it as the shearing operation takes place, the excess being sheared off on a cross line 85 just behind the point of contact of the guard against the plate edges, the guard being re-erected by its spring 40 when member 19 is thrown back. The other end being already square cut, after folding there is therefore an absolutely square cut as to both ends of the plates.

90 It will be understood that the sheets are placed on the machine with one end of the pack resting upon the guard 38, its other end lying inside the knife 20 on the folding member. The guard 38 is made of a stem or shaft fitted loosely in a receiving socket 39 at the end of the main frame and is supported upon a coil spring 40 at the bottom of the socket, so that it engages the ends of the plates as they are thrown over and co-operates with the gripping action in holding 95 them in position during the folding process, and is pushed downward into its casing and out of the way by contacting pressure of flange 19^a upon the upper side of the projecting pack when the table members are 100 brought into final folded position simultaneously with the shearing operation.

105 The many uses and advantages of my machine will be obvious to those who are familiar with this art. It is to be understood that the many changes or variations of mechanical construction or detail which may be made in the actual machine are to be considered as within the scope of my invention.

110 I claim:

115 1. A machine of the class described comprising a stationary table provided at its end with a resiliently mounted guard device, a movable member hinged to the table and adapted to fold thereupon, driving means 120 adapted to actuate the movable member, independently actuated laterally movable arms located inwardly of the table edges adapted to aline and resiliently grip metal sheets 125 upon the stationary table, fluid actuated 130

means for operating said arms simultaneously in opposite directions, and a knife fixed on the movable member, whereby to simultaneously fold the sheets and shear 5 their ends.

2. A machine for folding and shearing metal sheets composed of a stationary table provided at its end with a resiliently mounted guard device, a movable member adapted

10 to lie in open position in approximately the same plane as the table and to fold thereupon, a knife fixed on the outer edge of the stationary table, a co-acting knife on the outer edge of the movable member, driving

15 means adapted to actuate the movable member, and fluid actuated laterally operable lever mechanism having laterally movable arms extending upwardly through the table adapted to engage the sheets edgewise and

20 hold them in a fixed true position on the table and movable member, whereby the plates may be simultaneously folded and their ends sheared.

3. In a machine for simultaneously folding 25 and shearing metal plates, the combination of a stationary table member, a movable member adapted to supplement the table in receiving the metal plates and to fold thereupon, means for actuating the mov-

30 able member, a knife on the outer edge of the movable member, forks adapted to engage the metal plates laterally whereby to bring them into true position with relation to each other and with relation to the folding member and table, and fluid operated 35 actuating means for said forks, whereby to simultaneously fold the plates and shear their ends squarely.

4. In a machine for folding and shearing 40 sheet metal, a stationary table provided with laterally arranged clearance slots, a resiliently mounted guard device at one end of said table, a movable folding platen hinged to the stationary table having means adapt-

45 ed to fold it over upon said table, slidably mounted arms extending upwardly through

the clearance slots of the stationary table, and means for simultaneously moving said arms toward or from each other.

5. A machine for folding and shearing 50 metal plates composed of a stationary table, a movable member adapted to lie in open position in approximately the same plane as the table and to fold thereupon, driving means to actuate the movable member, forks 55 adapted to work through slots in the table and to grip the metal plates, air pressure operated means to actuate the forks, and a knife on the folding member, whereby metal plates of varying size may be simultaneously 60 folded and their ends sheared.

6. In a machine for folding and shearing sheet metal, a stationary table provided with an endmost stationary shear blade, a resiliently mounted guard device beyond said 65 shear blade, a movable folding platen hinged to said table having means adapted to fold it over thereon and provided with a terminal shear blade adapted to co-act with the table shear blade, laterally movable arms extend- 70 ing through portions of the table and platen adapted to engage sheets edgewise to straighten a pack of sheets, and means for simultaneously moving said arms toward or from each other.

7. In combination, a stationary table pro- 75 vided with an endmost stationary shear blade, a resiliently mounted depressible guard device located beyond the shear blade, a movable platen hinged to said table hav- 80 ing means adapted to fold it over thereon and provided with a terminal shear blade adapted to co-act with the table shear blade, and means for moving the sheets of a pack laterally to bring their side edges together 85 prior to folding and shearing them.

In testimony whereof I hereunto affix my signature in the presence of two witnesses.

OLIVER P. COLLINS.
